UNITED STATES PATENT OFFICE.

FRANK SPILL, OF RUTHERFORD, NEW JERSEY, ASSIGNOR TO RUTHERFORD COMB COMPANY, OF EAST RUTHERFORD, NEW JERSEY, A CORPORATION OF NEW JERSEY.

DESIGN FOR A BARRETTE.

42,527.

Specification for Design.

Patented May 14, 1912.

Application filed February 9, 1912. Serial No. 676,678. Term of patent 7 years.

To all whom it may concern:

Be it known that I, FRANK SPILL, a citizen of the United States, residing at Rutherford, county of Bergen, and State of New Jersey, have invented a new, original, and ornamental Design for Barrettes, of which the following is a specification, reference being had to the accompanying drawings, forming part thereof.

The figure is a face view of a barrette showing my new design.

The design consists of the open or cross-bar work a, giving a lattice like effect, surrounded by a frame border b of elongated form.

I claim—

The ornamental design for a barrette as shown and described.

FRANK SPILL.
